DES. 2021

Assign to

The Lowell Manufacturing Company, of the same place.

Letters Patent No. 1021-Dated Jan'y 17-1865.

Design for a Carpet Pattern.

The schedule referred to in this letter is intended making part of the same.

Shall whom it may concern.

Be it known that, Eleanor Key of Lowell, in the County of Middlesex and State of Massachusetts, have originated and designed a new pattern for carpets or other fabrics, of which the following is a full, clear and exact description, reference being had to the accompanying drawings, making a part of this specification.

A. A are scrolls running through the design on either side of which are the connected leaves B.B.

C.C. is a bar composed of blocks and dotted work, and bordered by scrolls which run diagonally through the design and when matched will form a diamond.

D.D. are parts of bars running crossways of the design.

1,2 and 3 and 4 are diamonds forming the ground of the design.

The colors employed for the different portions of the design may be varied to suit the taste or color of the manufacturer.

Class
